UNITED STATES PATENT OFFICE.

HENRY C. BENAGH, OF NASHVILLE, TENNESSEE.

COMBINED RAIL JOINT AND CHAIR.

SPECIFICATION forming part of Letters Patent No. 560,118, dated May 12, 1896.

Application filed January 14, 1896. Serial No. 575,521. (No model.)

To all whom it may concern:

Be it known that I, HENRY C. BENAGH, residing at Nashville, in the county of Davidson and State of Tennessee, have invented a 5 new and Improved Combined Rail Joint and Chair, of which the following is a specification.

My invention is in the nature of a combined joint and chair for rails, and it primarily has for its object to provide an improvement of 10 this character of a simple but effective construction that will tighten when the weight of a car is on the rail and be, as it were, an automatic working clamp and girder or chair fastening for a railroad-joint making a continuous rail.

My invention also has for its object to provide chair devices for the purposes stated which can be used with or without fish-plates or splice-bars, and in which the several parts 20 are so constructed and relatively arranged that there will be practically no thrust or bearing strain on the bolts as the car passes over the rail, thereby avoiding danger of the bolts breaking.

With other minor objects in view, which will hereinafter be referred to, my invention consists in the peculiar combination and novel arrangement of parts, such as will be first described in detail and then be specifically 25 pointed out in the appended claims, reference being had to the accompanying drawings, in which—

Figure 1 is a perspective view of my improvement, the same being adapted to be used 30 in connection with rail-joints having fish-plates. Fig. 2 is a transverse section of the same, taken on the line 2 2 of Fig. 1, the parts being shown in their normal position. Fig. 3 is a similar view showing the several parts 35 in their depressed position. Fig. 4 is a detail view of a portion of one of the rocker-chairs, having its end cut away to reduce the weight of material therein. Fig. 5 is a perspective view of my improved rail-chair, showing the 40 same provided with clamp or fish-plate members; and Fig. 6 is a view of a modified form 45 of a chair portion, hereinafter referred to.

My invention, while embodying a combined structure of rail joint and chair, more especially relates to an improved construction of 50 chair or joint-block, such as most clearly illustrated on Sheet 1 of the accompanying draw-

ings, by reference to which it will be seen the chair consists of a pair of joint-blocks A A', made solid, either of a malleable or 55 cast iron body, as shown in Figs. 1, 2, and 3, or a skeleton-like plate-steel body, formed in a manner similar to that shown in Fig. 6. Each of the joint-blocks has its bottom or cross-tie bearing portion made with two faces 60 B and C, arranged at obtuse angles to each other, one of which, C, however, is of such an angle that when the said blocks A A' are in their normal position they will seat flatly upon the cross-tie D and form the bearing- 65 base for the block.

The upper face of the blocks A A' is formed with an inner horizontal or tread portion E and an outer depressed or concaved portion e, which terminates at the hook or clamp 70 member F of the block, which is adapted to project over and engage the upper face of the base-flange g of the rail when such rail has the usual fish-plate members H, as shown on Sheet 1. 75

The base portions of the blocks A have horizontal vertical flanges or faces a², which when such blocks are at their normal position abut, as clearly shown in Fig. 2, the side portions of the blocks being concaved to reduce the 80 weight of such blocks.

The block or joint member A has a series of bosses A², having horizontal apertures a¹² to receive the head ends of the tie-bolts J, the nut ends of which are adapted to pass through 85 the apertures a¹³ in the bosses A³ of the sections A A', such apertures a¹² and a¹³ being made slightly conical or tapering to permit of a free movement of the sections A A' vertically without danger of breaking or snapping the bolts. 90

In practice the sections A A' are held from lateral displacement on the ties by the ordinary spikes, which are, however, not driven down tight, so as to admit of a slight vertical movement of the outer flanges a⁵ a⁵. From 95 the foregoing description, taken in connection with the accompanying drawings, it will be manifest that the construction and arrangement of the chair members A A' is of such a nature that when the weight of the car is on them they will assume the position shown in Fig. 3, the clamp members F F being the more tightly clamped against the flanges of the rail as the rail bears on the blocks A A'

in such a manner that they will rock inward, the points α being the fulcrum, thereby automatically making the joint or chair for the rail the tightest and most secure at the time it is most needed—when the car passes over it.

Instead of making the blocks A A' with solid base or tread portions, the outer ends, as also the portions intermediate the apertured bosses, may be cut away or reduced, as indicated at N in Fig. 4, and thereby materially lighten the blocks without the least impairing their strength.

In Fig. 5 I have shown my improved joint-blocks provided with integral fish-plate or clamp members L L, such form of combined chair and clamp being used when the rails are not provided with the usual fish or joint plates.

By providing the chair-blocks with clamp portions L L it will be readily understood that the down pressure of the rail will cause the blocks A A' to rock inward and the portion l of the clamp press tightly on the flange of the rail, while the portion l' bears tightly against the web in the direction indicated by the arrows 20 20.

Manifestly other variations in the details of structure may be made from that shown without departing from the broad idea of my invention, the essential features of which appear in the appended claims.

Having thus described my invention, what I claim, and desire to secure by Letters Patent, is—

35 1. A joint block or chair comprising a pair

of blocks each having clamp portions to engage the flanges of the rail, depressions in the top at the clamp ends their base portions being provided with a rocker-bearing, and nut and bolt devices for holding the said blocks 40 from lateral displacement as specified.

2. The combination with the rail and the tie of the joint-blocks A A', having the tread portion on the upper face terminating at the end in depressions, and clamp members adapted to project over and engage the flanges of the rail such blocks having rocker-bearings on the tie whereby to draw inward at their upper end as the car passes over them, and thereby cause the clamp members to tightly 45 50 clamp the rail-flanges and nut-bolt devices connecting the blocks said blocks all arranged as shown and for the purposes described.

3. The combination with the rail and the cross-tie, of the sections A A', having the rest portions for the rail terminating at the outer ends in depressions and clamp members, adapted to lap over and engage the top of the rail-flanges, and having their base portions 55 60 provided with rocker-bearings at a point outside the normal rest portion for the rails, and bolt and nut devices for connecting the blocks, said blocks having a limited free vertical play on the bolt as specified.

HENRY C. BENAGII.
